FEED LEG FOR ROCK DRILLS

Martin Worman, Phillipsburg, N.J., assignor to Ingersoll-Rand Company, New York, N.Y., a corporation of New Jersey

Filed Oct. 27, 1960, Ser. No. 65,342
5 Claims. (Cl. 137—596)

This invention relates to control valves and more specifically to valves of the type for controlling a feed leg for power tools such as rock drills.

Up to this time feed legs for rock drills have been single acting (power extensible, manually retractable) and a single valve element has been used to control the amount of air going to the leg. This valve merely controls the quantity as no directional control was required. With the advent of double acting feed legs (power extensible and power retractable) a directional control valve is now required incorporating a quantity flow control when extending the leg and must have means for immediate disconnect of the air pressure from both sides of the fluid motor (feed leg) for emergency conditions.

An object of this invention is to provide a directional control valve for a double acting feed leg for rock drills.

Another object of this invention is to provide a valve for rock drills and the like to control a double acting feed member being positive acting and of such character as to be capable of withstanding the high shock forces imparted thereto.

These and other objects of this invention will become apparent by referring to the following description and the accompanying drawing in which

FIGURE 1 is an elevational view of a rock drill and a feed leg therefor including a control valve device in accordance with the subject invention.

FIG. 2 is a sectional view taken on line 2—2 of FIG. 1.

FIGS. 3, 4 and 5 are sectional views taken on line 3—3 of FIG. 2, illustrating the valve in three operative positions,

FIG. 6 is a sectional view taken on line 6—6 of FIG. 2, and

FIG. 7 is a sectional view taken on line 7—7 of FIG. 2.

Referring now to FIG. 1, a rock drill 10 is conventionally shown having a bracket 12 for receiving a double acting feed leg 14. The feed leg 14 has motor chambers 14A and 14B, and, a ground engaging portion 16 at the free end thereof. The drill feed line 18 is the only external conduit associated with the drill as the remaining air passages are incorporated within the structure. The drill 10 has a handle 20 attached thereto which houses a flow control valve 74 and a directional control valve 90 as will be described.

The drill 10 has a tapered transverse bore 11 at the bottom of the backhead of the drill body which is intersected by three air passages 10A, 10B and 18A as may be seen in FIG. 2. The air passages 10B and 10A connect the bore 11 to the top and bottom motor chambers 14A and 14B, respectively, of the feed leg 14. The passage 18A is an extension of the air supply line 18 and connects the control valve device for the drill to the bore 11.

The handle 20 is formed of a grip 22 mounted in a transverse bore 26 in a handle bracket 24 and forms, in part, the flow control valve housing 70. The bracket 24 has a leg portion 30 received in the tapered bore 11 in

2

the backhead of the drill 10 and is locked therein by a nut 28. The leg portion 30 has three spaced annular grooves 32, 34 and 36 forming chambers within the bore 11, the chambers communicating with the passages 18A, 10A and 10B, respectively. The intervening lands between the annular grooves form seals thus segregating each of the formed chambers from one another. The bracket 24 has a valve bore 40 threaded at one end as at 42, and, an end wall 44 with an opening 46 therethrough being smaller in size than the bore itself.

The chamber formed by the annular groove 36 is connected to the transverse bore 26 by an internal passage 48 while the chamber formed by the annular groove 34 communicates with a passage 50; the passage 50 being connected to the valve bore 40 by a passage 54. The chamber formed by the annular groove 32 communicates with an internal passage 52; the passage 52 being connected to the valve bore 40 by passage 58. The transverse bore 26 in the bracket 24 is further connected to the valve bore 40 by two passages 60 and 62 while a port 64 connects the bore 26 to atmosphere. For simplicity, the passage 62, as shown, connects with the passage 48 instead of directly connecting to the bore 26.

The grip 22 is comprised of three major parts, a fixed tubular gripping portion 70, a rotational gripping portion 72 outward of the fixed portion 70 and an internal rotary valve 74 operatively connected to the portion 72. The tubular portion 70 has a reduced end 68 sweated into or otherwise retained in the transverse bore 26 of the bracket

20 and is held rigid therein. The reduced portion 68 has a plurality of drilled holes which communicate with the various passages that intersect the bore 26 and for descriptive purposes will be considered as an integral part of the specific passage with which they communicate.

35 The rotary valve 74 has a chamber 76 and three ports

78, 80, and 82 axially spaced from one another and adapted to communicate with the passages 48, 60 and 64, respectively. The inner wall of the member 70 or the outer wall of the valve 74 has an annular groove 84 in

40 communication with the passage 48 and the port 78 in such a manner that the chamber 76 is in constant communication with the passage 48 regardless of the angular position of the valve 74. The ports 80 and 82 are angularly disposed relative one to the other and are adapted

45 to communicate with the passage 60 and the port 64, respectively. The valve 74 has a metering groove 86 which extends about one quarter of the periphery of the valve from the port 80 and reduces in size toward its end remote from the port as may be seen in FIG. 7. A second metering groove 88 similar to the groove 86 extends from the port 82 in a reverse direction. The grooves 86 and 88 are metering grooves for the rotary valve 74 as will be further explained.

50 A slide valve 90 is received in the bore 40 and has a reduced plunger portion 92 extending through the opening 46 in the end wall 44 of the bracket arm 24. The valve 90 has a blind bore 94 to receive a spring 110. There is an alternate series of lands and grooves 100, 102, 104, 106, and 108, respectively, which form the outer surface of the valve 90. Spring 110 is held in place by a plug 112 received in the threaded portion 42 of the valve bore 40 to urge the valve 90 into engagement with the wall 44. The spring 110 normally holds the valve 90 in its extreme left-hand position relative to the drawings as

shown in FIG. 3 wherein the plunger side of the land 100 abuts the inner surface of the wall 44.

With the valve 90 in this position, the flow control valve 74 may be so positioned as to regulate the quantity of flow from the fluid source, after passing across the valve 90, to the top chamber 14A of the feed leg 14 for extending the leg. It is only when the valve 90 is in this position that the quantity flow control valve 74 becomes an operative part of the valve device. Pressure fluid entering the drill 10 via the feed line 18 passes across the drill control valve 90 and is ported to the rotary control valve 74 via the internal passage 18A, the chamber formed by the annular groove 32 within the bore 11, the passage 52, the intermediate passage 58, across the annular groove 106 of the valve 90 within the bore 40, through passage 60 and the port 80 to the chamber 76. The pressure fluid in the chamber 76 is then directed to the upper chamber 14A of the feed leg 14 via the port 78, the passage 48, the chamber formed by the annular groove 36 in the bore 11, and the internal passage 10B in the drill 10. The chamber 76 always communicates with the passage 48 due to the annular groove 84 which extends around the valve 74 and intersects the ends of the port 78 and the bore 48.

As may be seen in FIGS. 6 and 7, the ports 82 and 80 have reversely extending throttling grooves 88 and 86 respectively to control the fluid entering the chamber 76 and also to control the amount of pressure fluid therefrom which may be discharged to atmosphere through the ports 82 and 64. Rotation in one direction of the valve 74 will rotate the port 80 away from the passage 60 providing progressively restricted flow through metering groove 86, thus finally cutting flow of pressure fluid to the chamber 76 and at the same time cause the port 82 to fully align with the port 64 and thus the top chamber 14A of the feed leg 14 would be fully vented. Conversely, rotation in the other direction of the valve 74 would cause the port 80 to fully align with the passage 60 to permit maximum flow of pressure fluid into the chamber 76 and at the same time rotate the metering groove 88 out of alignment with the exhaust port 64 and thus full pressure fluid would then be delivered to the top chamber 14A of the feed leg 14. Simultaneously, the bottom chamber 14B of the feed leg is vented via the passage 10A, the annular groove 34, the passages 50 and 54, the bore 40 and a hole 114 in the wall of the housing of control valve 90.

When the operator commences his drilling operation, he may position the valve 74 to obtain the desired force acting to extend the leg 14. As long as the operator is drilling in similar ground structure, he would not want to change the setting of the rotary control valve 74. Should an emergency arise, such as breaking a drill steel, the operator would merely have to depress the plunger 92 to cause valve 90 to shift to the position as is shown in FIG. 4 which we may call a feed release position. Pressure fluid in the passage 52 flows into the valve bore 40 into the annular groove 106. However, the lands 104 and 108 now prevent the fluid from flowing to any other passage and thus is cut off from the feed leg 14. Feeding of the drill is thus discontinued.

When the operator completes his drilling operation with the valve 90 in the position shown in FIG. 3 and desires to move to another location to drill a second hole, he merely depresses the plunger 92 to its full extent as shown in FIG. 5 which is the power retract position. As may now be seen, air in the passage 52 now enters the bore 40 via the passage 58 in the chamber defined by the annular groove 106 and goes to the lower chamber 14B of the feed leg 14 via the passage 54, the passage 50, the chamber defined by the annular groove 34 in the bore 11 and the passage 10A. At the same time, the upper chamber 14A of the leg 14 is vented to atmosphere via the passage 48, the passage 62, the chamber in the bore 40 defined by the annular groove 102, and port 43. As may be more clearly seen, the pressure

fluid does not enter the rotary control valve 74 when the valve 90 is in the power retract position.

While I have shown and described specific forms of this invention, it is to be understood that various changes and modifications may be made without departing from the spirit of the invention as set forth in the appended claims.

I claim:

1. A valve device comprising a housing having an inlet passage, an exhaust passage, a delivery passage, and a connecting passage; a valve movable in said housing from one terminal position in which said valve connects the delivery and exhaust passages and simultaneously connects the connecting and inlet passages to a second terminal position in which said valve connects the delivery and inlet passages and simultaneously closes the connecting passage; said valve movable to a position intermediate the terminal positions in which said valve closes the inlet, delivery and connecting passages; said housing having a second delivery passage and an exhaust port; and a second valve to connect the connecting passage to the second delivery passage and the exhaust port, and being movable to vary the extent of communication of such passages and port to control the flow through the second delivery passage.

2. The valve device according to claim 1 and the second valve being movable between terminal positions to provide an unrestricted connection between the connecting and second delivery passages and simultaneously to close the exhaust port in one of the terminal positions, and to provide an unrestricted connection between the second delivery passage and the exhaust port and simultaneously to close the connecting passage in the other of the terminal positions.

3. A valve device comprising a housing having an inlet passage, a pair of exhaust passages, a delivery passage, and a connecting passage; a valve movable in said housing from one terminal position to connect the delivery and one of the exhaust passages and simultaneously to close the connecting and inlet passages to a second terminal position to connect the delivery and inlet passages and simultaneously to close the connecting passage; said valve movable to a position intermediate the terminal positions to close the inlet, delivery and connecting passages; said housing having a second delivery passage and an exhaust port, said second delivery passage being closed by the valve in the first terminal and intermediate positions and connected to the other exhaust passage by the valve in the second terminal position; and a second valve to connect the connecting passage to the second delivery passage and the exhaust port, and movable to vary the extent of communication of such passages and port to control the flow through the second delivery passage.

4. A valve device comprising a housing having an inlet passage, a pair of exhaust passages, first and second delivery passages, and a connecting passage; a valve movable in said housing from one terminal position to connect the first delivery and one of the exhaust passages and simultaneously the connecting and inlet passages to a second terminal position to connect the first delivery and inlet passages and simultaneously the second delivery and the other of the exhaust passages; said valve movable to a position intermediate the terminal positions to close the inlet, first and second delivery, and connecting passages; said housing having an exhaust port; and a second valve to connect the connecting passage to the second delivery passage and the exhaust port, and being movable to vary the extent of communication of such passages and port to control the flow through the second delivery passage.

5. The valve device according to claim 4, wherein the second valve formed is movable between two terminal positions to provide unrestricted flow of the pressure fluid to the second delivery passage in one of the terminal positions and to progressively restrict such flow

as it moves to the other of the terminal positions for substantially blocking the flow to the second delivery passage and simultaneously passing such flow to the exhaust port.
